US00D822037S

(12) **United States Design Patent** (10) **Patent No.:** **US D822,037 S**
Mariet et al. (45) **Date of Patent:** **** Jul. 3, 2018**

(54) **DISPLAY SCREEN OR PORTION THEREOF WITH GRAPHICAL USER INTERFACE**

(71) Applicant: **Waymo LLC**, Mountain View, CA (US)

(72) Inventors: **Robertus Christianus Elisabeth Mariet**, Sunnyvale, CA (US); **Manuel Christian Clement**, Felton, CA (US)

(73) Assignee: **Waymo LLC**, Mountain View, CA (US)

(**) Term: **15 Years**

(21) Appl. No.: **29/582,394**

(22) Filed: **Oct. 27, 2016**

Related U.S. Application Data

(62) Division of application No. 29/537,066, filed on Aug. 21, 2015, now Pat. No. Des. 776,681, which is a division of application No. 29/438,651, filed on Nov. 30, 2012, now Pat. No. Des. 739,423.

(57) **CLAIM**

The ornamental design for a display screen or portion thereof with graphical user interface, as shown and described.

DESCRIPTION

The patent file contains at least one drawing executed in color. Copies of this patent publication with color drawing(s) will be provided by the Office upon request and payment of the necessary fee.

The FIGURE is a front view of a display screen or portion thereof with graphical user interface according to our design. The dot-dash broken lines showing the display screen or portion thereof form no part of the claimed design. The dash-dash broken lines showing portions of the graphical user interface form no part of the claimed design.
